UNITED STATES PATENT OFFICE.

HOWARD R. HUGHES AND RUDOLPH C. KULDELL, OF HOUSTON, TEXAS; SAID KULDELL
ASSIGNOR TO HUGHES TOOL COMPANY, OF HOUSTON, TEXAS.

CROSS-ROLLER DRILL.

Application filed April 20, 1922. Serial No. 555,797.

To all whom it may concern:

Be it known that we, HOWARD R. HUGHES and RUDOLPH C. KULDELL, citizens of the United States, residing at Houston, Harris

5 County, Texas, have invented a certain new and useful Improvement in Cross-Roller Drills, of which the following is a full, clear, and exact description, such as will enable others skilled in the art to which it appertains to make and use the same.

10 Our invention relates to an improvement in rotary earth boring drills and has particular application to the retaining means to be used in securing in position the shaft 15 of the cross roller cutters in the so-called cross roller bit.

The object of our invention is to provide a means for retaining the cutter shaft of a cross roller bit in position, so that it may 20 be easily removed.

Another object is to provide a retaining means for the cutter shaft in a cross roller bit which will permit the cutters to be mounted in position on the shaft and the 25 shaft to be then inserted in position in the head and there secured in place with the least possible amount of manipulation.

Other objects and advantages of our improvement will be apparent from the more 30 detailed description which follows, and the points of novelty therein will be set forth in the claims appended hereto. Referring to the drawings, forming a part of this specification, and wherein like numerals of reference 35 are applied to like parts in the separate views; Fig. 1 is a side elevation of a cross roller bit in which our invention is employed. Fig. 2 is a central longitudinal section on a plane parallel with the cross 40 roller shaft, and Fig. 3 is a transverse section on the plane 3—3 of Fig. 2.

In the type of bit to which our invention has been applied, there is a head, approximately cylindrical midway between its ends. 45 It is tapered upwardly toward the upper end and has a threaded shank 2 for attachment to a drill collar of ordinary construction, not shown. At the upper end of shank 2, a small threaded shank or extension 3 is 50 provided by means of which the lubricator container may be secured to the head of the drill. The lower end of the head is beveled or recessed on opposite sides as shown at 4; thus, providing seats for the two inclined 55 side cutters 5. Said cutters are secured upon

pins 6 in the usual manner. These cutters and their method of mounting are not a part of our invention and further description is unnecessary.

Between the two side cutters and extending diametrically through the head is a cross shaft 7. To receive this shaft and the cross roller cutters, the lower face of the head is formed with two central chambers or pockets 8, there being between these pockets 60 a central wall or web 9. At the outer ends of these chambers the wall 10 of the head extends downwardly to provide a support for the opposite ends of the cutter shaft 7. Said walls 10 are provided with a central 65 opening 11 cylindrical in outline and materially larger than the end 2 of the cutter pin. Below the openings 11 slots 13 are formed in the walls through which openings the ends 12 of the pin may pass. Each opening 70 11 about the end 12 of the pin provides a seat for a retaining ring 14 which is adapted to fit about the end of the shaft and form a seat or support within which the shaft is retained. A diametrical opening 15 is formed 75 through the bearing ring 14 and a similar opening 16 is formed in each end of the cutter shaft; thus, when the shaft has been forced into position and the locking ring 14 inserted in position over the end thereof, the 80 cotter pin 17 may be inserted through the registered openings 15 and 16 to hold the ring 14 in position. To allow the insertion of the cotter pin 17 the wall 10 of the chamber is provided with an outer vertical groove 85 18 above the pin.

The central portion of the pin 7 is squared as is shown at 19 to fit within a square slot 20 in the central web 9. It will thus be apparent that when it is desired to mount the 90 cutters shown at 21 within the head of the bit, said cutters may be placed in position upon the cutter pin or shaft. The outer face of the end cutter of each group is recessed to receive a washer 25 which is fixed 100 to the shaft by being upset and driven into a groove 26 and openings 27 in the said shaft 7. This holds the cutters securely mounted in correct position on the shaft. When thus mounted, the assembled cutters and pin 105 20 may be inserted upwardly through the slots 13 in the outer walls and 20 in the central web into operative position. The locking rings 14 will then be slid into the recesses 11 about the ends of the pin and the cotter 110

pins then used to retain the said rings in position on the pin. As will be noted particularly from Fig. 1 the pin and locking ring together are materially larger than the slot 13; thus, preventing the lateral movement of the said pin and acting to retain it securely in position.

When in actual operation the cutters will be lubricated by the system now usually employed in successful roller drills. The cutter pin will be provided with a central channel shown in dotted lines at 22 and from this channel branching ducts will lead to the bearings of the cutters. The channel 22 will be connected by means of a passage 23 in the head to the lubricator which will be secured upon the shank 3 previously described. Water from the drill stem will find a passage downwardly through the head of the bit by means of water channels 24 and thus be discharged upon the cutters during their operation.

The particular advantages of our improvement of cutter mounting, lies largely in the convenience and rapidity by means of which the cutters may be assembled in the head. It also makes it possible to provide several cutter shafts upon each of which may be mounted a separate set of cutters. These cutters may be assembled on the shaft in the shop and may be quickly mounted in the head on the derrick floor as previously described. There is practically no possibility of the shaft being loosened or broken and lost in the hole. When one set of cutters have become dulled, it will be possible to quickly remove the same together with their cutter pin and substitute therefor a new set of cutters. Very little time will thus be lost and there will be no danger of mounting cutters in incorrect position.

Having thus described our invention, what we claim is new and desire to protect by this patent is:

1. In a rotary earth boring drill, a head having two cutter mounting recesses or chambers in its lower end, a cutter shaft extending diametrically across said head and said chambers, cutters on said shaft in said chambers, said chambers having lateral openings of larger diameter than the diameter of said shaft, and slots leading downwardly from said openings of the same width as said shaft, retaining rings adapted to fit over the ends of said shaft and into said openings and means to retain said rings on said shaft.

2. In a rotary earth boring drill, a head having two cutter mounting chambers in its

lower end providing a central and two side walls, cutters in said chambers and a cutter supporting shaft extending through said chambers diametrically of said head, said shaft fitting in a squared slot in said central wall and in slots in said side walls, said outer slots being shaped to receive said shaft and enlarged at their upper ends and a retaining ring in said enlarged portion about said shaft and means to hold said ring in place.

3. In a cross roller drill, a head, a support at the lower end of said head for the cross cutters comprising a central and two side supporting walls, a cutter shaft having a squared central portion, said central wall having a squared slot to receive it, said side walls having vertical slots to receive the ends of said shaft, said slots being enlarged at their upper end and a retaining ring adapted to fit about said shaft in the manner described.

4. In a cross roller drill, a head, a support at the lower end of said head for the cross cutters comprising a central wall and two side walls, said walls having vertical slots, the slots in said side walls being enlarged at the upper ends, cross cutters and a shaft for said cutters fitting in said slots, a retaining ring slidable on to the ends of said shaft and fitting in said enlarged portion of the slots and a cotter pin engaging each ring and passing through said shaft to retain said ring in position.

5. In a rotary earth boring drill, a head, side cutters and cross rollers thereon, a support for said cross rollers comprising a shaft, forwardly projecting supporting walls for said shaft, said walls having slots therein, said slots being enlarged at their upper ends to receive said shaft, retaining rings about said shaft in said enlarged ends of said slots, means to retain said rings in place, and means to prevent rotation of said shaft.

6. In a rotary earth boring drill, a head, side cutters and cross rollers thereon, a support for said cross rollers comprising a shaft, means to hold said cutters assembled on said shaft, supporting walls having vertical slots to receive said shaft, said slots having enlarged upper ends, retaining rings fitting about said shaft in said enlarged upper ends of said slots, and means to retain said rings in place.

In testimony whereof, we hereunto affix our signatures, this the 28 day of March, A. D. 1922.

HOWARD R. HUGHES.
RUDOLPH C. KULDELL.
